Patented Apr. 3, 1917.

UNITED STATES PATENT OFFICE.

J. ALPHONSE STE MARIE, OF LAPRAIRIE, QUEBEC, CANADA.

RESPIRATOR.

1,221,387.

Specification of Letters Patent.

Patented Apr. 3, 1917.

Application filed July 11, 1916. Serial No. 108,741.

To all whom it may concern:

Be it known that I, J. A. STE MARIE, a subject of the King of Great Britain, residing at Laprairie, in the Province of Quebec and Dominion of Canada, have invented new and useful Improvements in Respirators, of which the following is a specification.

The invention relates to respirators, and has for its primary object to provide a device 10 of this character wherein fresh air can be inhaled from without while within an enclosure without possibility of the inhalation of dirt, dust, snow or foreign matter.

Another object of the invention is the provision of a device of this character wherein the construction thereof is novel in form so that the breathing of a person can be effected naturally and during respiration fresh air will be inhaled for passage into the lungs 20 of the user.

A further object of the invention is the provision of a device of this character which is extremely simple in construction, thoroughly reliable and efficient in its operation, 25 strong, durable and inexpensive in manufacture.

Other objects will be in part obvious and in part hereinafter set forth.

The invention accordingly consists in the 30 features of construction, combination of elements and arrangement of parts which will be exemplified in the construction herein-after described, and the scope of the application of which will be indicated in the appended claim.

In the accompanying drawings:

Figure 1 is a side elevation of a respirator constructed in accordance with the invention;

Fig. 2 is a vertical longitudinal sectional view through the respirator hood;

Fig. 3 is a vertical sectional view through the inlet cap;

Fig. 4 is a sectional view on the line 4-4 of Fig. 2;

Fig. 5 is a sectional view on the line 5-5 of Fig. 2;

Fig. 6 is an end elevation of the hood.

Similar reference characters indicate corresponding parts throughout the several views of the drawings.

Referring to the drawings in detail, the respirator comprises a substantially cone shaped body 10 forming a hood having at one end a nipple 11, while its opposite open end 12 is formed with a nose bridge 13, the

body 10 being formed at its open end 12 with a marginal edge which conforms to the shape of the face and nose adjacent the mouth of the user. In other words, the body 10 is shaped to anatomically fit the user's nose and face.

Fitted over the nipple 11 of the hood 10 is one end of a flexible tube 14 which has mounted on its opposite end a conical shaped cap 15 which is held spaced from the inlet end of the tube 14 through the medium of a spider 16 so that air can be sucked in through the inlet end of the tube into the body 10 when the respirator is in use. It is of course understood that the inlet end of the tube 14 is extended without an inclosure for communication with the atmosphere so that fresh or pure air can be inhaled for passage into the lungs of the user. The cap 15 serves to protect the inlet end of the tube 14 and also in this inlet end is a gauze screen 17 which prevents the ingress of dust, dirt or other foreign matter during inhalation. The nipple 11 is formed with a central bore or passage 18 which has at opposite ends thereof guides 19, in which is slidably mounted the stem 20 of a disk valve 21 which is adapted to open inwardly of the body 10 to permit the inhaling of fresh air, the stem 20 being surrounded by means of a coiled spring 22 which serves to normally hold the valve 21 closed or seated against the inner end of the bore 18 in the nipple 11. The stem 20 is formed with a stop 23 which limits the sliding movement thereof in the guides 19 so as to limit the opening movement of the valve 21 when the device is in use.

Formed at the lowermost side of the body or hood 10 is an outlet nipple 24 having a bore 25 provided at opposite ends with guides 26 in which slides centrally thereof a valve stem 27 carrying a disk valve 28 which opens outwardly of the body or hood 10 and is normally seated upon the outer end of the nipple 24 to close the same. The stem 27 has surrounding it a spring 29 which normally seats the valve 28 and on the expelling of air through the nostrils or nose of the user the valve 28 will be automatically unseated for the exhaustion of the air from the body or hood 10 during respiration.

Fitted on the nipple 24 is a foraminous or wire mesh cap forming a guard 24' for the valve 28 so as to avoid any interference with the working of the valve from without the device, that is to say, the guard or cap 24'

envelops the valve to protect it from contact with external objects and especially when the device is in use by a person when occupying a bed to obviate the bed covering interfering with the working of said valve, as will be obvious.

Having thus described my invention, I claim:

10 A respirator comprising a hood having an open end shaped to receive the nose and mouth of the user, nipples formed at spaced points on and projecting outwardly from the hood, valve seats carried by the respective

opposite ends of the nipples, valve stems operating through the nipples and having 15 valves to engage the valve seats, means arranged wholly within the nipples to maintain the valves normally seated, and co-operating means carried by the nipples and valve stems to limit the opening movement of the valves, each of the nipples including a cylindrical free projecting portion to receive a tube.

20 In testimony whereof I affix my signature.

J. ALPHONSE STE MARIE.
